UNITED STATES PATENT OFFICE.

JOHN SZÁRAZ, OF HERSCHEL, SASKATCHEWAN, CANADA.

PIPE.

Application filed September 15, 1927. Serial No. 219,595.

This invention relates generally to smoking pipes, and has more particular reference to readily cleanable smoking pipes.

The invention has for an object the provision of a readily cleanable smoking pipe of simple construction and arrangement of parts which may be manufactured and sold at a reasonable cost.

When a pipe is smoked the bowl becomes charred and gives an unpleasant odor. The inner sides of the bowl may be scraped to remove this charring. The pipe is adapted for thorough and convenient scraping and cleaning by providing a removable closure at the bottom of the bowl.

For further comprehension of the invention and of the objects and advantages thereof of reference will be had to the following description and accompanying drawing and to the appended claims in which the various novel features of the invention are more particularly set forth.

Referring to the accompanying drawing forming a material part of this disclosure:

Fig. 1 is a perspective view of a pipe constructed according to this invention.

Fig. 2 is a vertical sectional view taken on the line 2—2 of Fig. 1.

Fig. 3 is a view similar to Fig. 2, but disclosing a modified form of the invention.

Fig. 4 is another similar view, disclosing another modification.

Fig. 5 is another similar view, disclosing another modification.

Fig. 6 is another similar view disclosing another modification, but in this view a fragmentary portion of the front of the pipe is shown.

Fig. 7 is a longitudinal central vertical sectional view of a pipe constructed according to a modification of the invention.

Fig. 8 is a vertical sectional view, taken on the line 8—8 of Fig. 7.

The reference numeral 10 indicates generally the bowl of a pipe having a stem 11 with mouth piece 12 connected therewith. The bowl 10 has a customary top opening 13, and a special bottom opening 14, preferably tapered, and closed by a cork or stopper 15 forced therein.

In Fig. 3 the stopper 15 is formed of a cover portion 16 and a filler portion 17.

In Fig. 4 the bowl 10 has a threaded bottom opening 14 and a stopper 15^a threadedly engaged therein.

The modification of the invention disclosed in Fig. 5 illustrates the bottom opening 14 of the bowl 10, closed by a cover 18 hingedly connected to the bowl at 19, and provided with a small projection 20 engaging in a niche 21 in the bowl. When the cover is forced open about hinge 19, the projection 20 is forced from engagement in the niche 21.

In Fig. 6, the bowl 10^a has elongated recesses 22 communicating with its outer side, and hooks 23 are provided at their upper ends in these recesses, as at 24. The lower ends of the hooks project through apertures 25 into the bowl, and engage in a peripheral groove 26 in the stopper 15^b engaged in the bottom opening 14^b of bowl 10^a. The hooks 23 may be manually moved to disengage from the peripheral groove 26, and then the stopper may be drawn from the bottom of the bowl.

Figs. 7 and 8 illustrate a pipe with a bowl 27 having an aperture 28 at its bottom, threadedly engaged by a stopper 29 integral with stem 30 which has a mouthpiece 31 connected thereto. The bowl is formed with elongated recesses 22, and hooks 23 are pivoted at their upper ends in these recesses, as at 24. The lower ends of the hooks project through apertures 25 and engage in apertures 26^a in the stopper 29.

The operation of the invention consists in removing the stoppers so that the bowls may be cleaned of charrings, by scraping, or the like. Upon replacing the stoppers the pipe is ready for use, and the bowls may be filled with tobacco.

While I have shown and described the preferred form of my apparatus as an example of the many ways of practically constructing the same, it is to be understood, that such changes may be made in the general arrangement and in the construction of the minor details thereof, as fall within the scope of the appended claims, without departure from the principle involved.

Having thus described my invention what I claim as new and desire to secure by United States Letters Patent is:

1. In a pipe of the class described, a pipe bowl formed with recesses extending from near the top edge thereof, downwards along the outside to near the bottom edge, and then inwards to the interior of the bowl, and arranged for housing pivotal clamping hooks against projecting outwards from the sur-

face of the bowl, and the said clamping hooks being adapted for holding a bottom stopper in the pipe bowl.

2. In a pipe of the class described, a pipe bowl formed with recesses extending downwards along the outside and then inwards to the interior of the bowl, and clamping hooks

pivottally mounted in the said recesses, and arranged for normally lying within the outer surface of the bowl, and adapted for holding a bottom stopper in the bowl.

In testimony whereof I have affixed my signature.

JOHN SZÁRAZ.
